F. POWELL

UNITED STATES PATENT OFFICE

162,470

PLAQUE

Frank Powell, Miami, Fla.

Application December 20, 1950, Serial No. 13,506

Term of patent 7 years

(Cl. D29—23)

To all whom it may concern:

Be it known that I, Frank Powell, a citizen of the United States of America, residing in Miami, county of Dade, and State of Florida, have invented a new, original, and ornamental Design for a Plaque, of which the following is a specification, reference being had to the accompanying drawing, forming part thereof.

Fig. 1 is a plan view of a plaque showing my new design.

Fig. 2 is an edge view thereof.

I claim:

The ornamental design for a plaque, substantially as shown.

FRANK POWELL.
